John P. Tarbox

UNITED STATES PATENT OFFICE.

JOHN P. TARBOX, OF GARDEN CITY, NEW YORK.

SPARK-PLUG CLEANER.

Application filed March 12, 1921. Serial No. 451,725.

To all whom it may concern:

Be it known that I, JOHN P. TARBOX, a citizen of the United States, residing at Garden City, in the county of Nassau and State 5 of New York, have invented certain new and useful Improvements in Spark-Plug Cleaners, of which the following is a specification.

The spark plug cleaner of my invention 10 is designed to be used in lieu of pocket knives and files now commonly used to clean plugs. A spark plug cannot be both quickly and thoroughly cleaned by these or similar implements. There are many reasons for 15 this. These implements are not adapted for ready manipulation in the space in which the fouling deposits lie, they do not make extended or effective contact with the surfaces to be scraped, and they often do not 20 reach to the bottoms of the spaces between the insulating core and the shell. Such spaces are often so deep that one cannot see far enough into them to be sure that the cleansing is thorough.

25 The implement of my invention is shown in the accompanying drawings of which, Figure 1 is a perspective view,

Figure 2 a longitudinal section of one end,

Figure 3 a longitudinal section of the opposite end,

Figure 4 an end elevation, and

Figure 5 is a view of a plug partly in section showing the implement in use.

The body of the implement 10 is formed 35 of an elongated substantially rectangular blank of metal or other material. It is a substantially rectilinear channel strip transversely of arcuate section and therefore of hollow substantially semi-cylindrical form.

40 The curvature of the arcuate section may or may not be that of a true circle. If so it is formed on a diameter intermediate the external diameter of the porcelain core of the plug and the internal diameter of the metal shell. In any event the curvature is 45 such that one end of it may be readily projected longitudinally into the annular space between the insulated core and the metal shell of the plug and it may be further projected the full length of the annular cavity.

On the opposite ends of this strip are formed a plurality or multiplicity of prongs 55 11. The extremities of these prongs are in the one case slightly in-turned and in the other case slightly out-turned at an acute angle, being deflected laterally of the main

body in each case. They are sharpened to form acute angled composite scraping edges as shown particularly in Figures 2 and 3. These edges are substantially at right angles 60 to the body of the cleaner. Both the prongs and their ends are properly tempered, the prongs to impart to them an appropriate degree of flexibility, and the extremities to impart hardness. The temper of the prongs 65 and the extremities may be similar or dissimilar according as conditions require.

The use of the implement exemplified in Figure 5 is very simple. First one end is inserted in the plug between the insulating 70 core 13 and the metal shell 14, pressed against the shell or the core as the case may be, reciprocated up and down a few times on all portions of the surface, and then the other end is similarly inserted and reciprocated, whereupon the plug is thoroughly cleansed of all deposits. In the illustration in Figure 5 the end having the out-turned prong ends is inserted and the shell is in process of being cleaned. By appropriate 75 pressure as the implement is reciprocated deposits of any degree of hardness found in practice may be quickly and thoroughly removed. Moreover the removed deposits are scraped entirely out of the cavity and are 80 not rammed into the bottom. The length and flexibility of the prongs enable the scraping ends 12 to be pressed into close fitting engagement with the surfaces to be scraped irrespective of variation in size and 85 irregularities in the curvature of the surfaces to be scraped. Thus an implement of one size can be used on several different sizes of plug. The top surfaces of the insulating core and the shell may quickly and 90 thoroughly be scraped by the use of that end of the implement having the out-turned prongs. The spring of the prongs further permits the implement to be deflected slightly to reach the surfaces lying immediately beneath any overhanging electrodes, as for instance electrode 15.

The metal of which the implement is made may be made of a thickness equal to an appropriate gap between the electrode terminals and used as a gauge of this gap as illustrated in dotted lines in Figure 5. Still further one side of it may be roughened as at 16 and appropriately tempered to constitute a file surface to polish the electrode 110 points by reciprocating movement between them.

This implement is simplicity itself, most easy to manipulate, most effective in its action, most adaptable to its several uses, and most inexpensive.

5 The implement may be made by any of several different processes. For instance it may be die punched in two operations from flat strip material. The first operation will sever the length of the strip, and form the 10 prongs, the kerfs between the prongs being made of sufficient dimension to insure good die cutting. By the second operation the formed strips are rolled into arcuate section and the ends of the prongs respectively in- 15 turned and out-turned. It is to be noted that turning the ends of the prongs in causes their extremities to lie on a circle of less radius than formerly whereby the kerfs between them are narrowed and the action is 20 thereby rendered more effective. The same rolling operation may form the file surface 16 or it may indeed be done by the first operation. The completed implements are ground as indicated in Figures 2 and 3 by 25 pressing their ends against flat grinding surfaces, and they may be tempered in bulk in appropriate furnaces.

Another method of forming them consists 30 in making use of tubular material of a diameter that is of the arcuate section desired, and sawing the material into strips by thirding or quartering it lengthwise, and sawing the prongs. The saws may be arranged singly, in groups of two or more or in gangs in 35 an appropriate machine. Circular saws may be readily used in gangs at appropriate angles in the machine and the tubing fed longitudinally thru the machine, being longitudinally cut into strips by a continuously 40 acting set of saws and having the prongs formed by an intermittently acting set of saws. Transverse saws will sever the implements from each other so as to leave prongs of equal length on each, and the ends of the 45 prongs may be turned by suitable forming irons or dies located along the path of movement of the material.

According to still a third method, flat strip material or any other flat material may 50 be used and the prongs saw-kerfed by saws in gangs after the material is cut into strips. The forming to the requisite arcuate section may then be done by dies as a third operation.

55 Still further, manufacture may be from multiple parts separately fabricated and assembled together to constitute the whole, instead of the one piece fabrication of integral stock.

60 Obviously while simple there are nevertheless possibilities of a number of modifications of this invention without departing from its fundamental nature. I desire the annexed claims to cover all such modifications.

What I claim is—

1. A spark plug cleaner comprising an elongated rectilinear channel strip of sheet metal adapted to be projected axially into a spark plug to be cleaned and having an extremity deflected laterally to a slight extent to form an arcuate scraping edge. 70

2. A spark plug cleaner of hollow semi-cylindrical form comprised at one end of a multiplicity of flexible scraping prongs each of which has a scraping edge projecting laterally. 75

3. A spark plug cleaner of hollow semi-cylindrical form comprised at one end of a multiplicity of flexible scraping prongs the extreme tip of each of which is deflected laterally to form a composite flexible scraping edge. 80

4. A spark plug cleaner of hollow semi-cylindrical form comprised at one end of a multiplicity of longitudinally extending flexible scraping prongs the extreme tip of each of which is deflected laterally to form a composite flexible scraping edge. 85

5. A spark plug cleaner of hollow semi-cylindrical form comprised at one end of a multiplicity of flexible scraping prongs the extreme tip of each of which is deflected inwardly of the form to constitute a composite inwardly projecting flexible scraping edge. 90

6. A sheet metal spark plug cleaner formed from a substantially rectangular blank into hollow substantial semi-cylindrical shape embodying a number of longitudinally extending flexible prongs at one end which prongs have their extreme tips bent laterally of their bodies to a slight extent and terminating commonly in a plane substantially at right angles to the axis of the cleaner wherein they together form a composite flexible scraping edge of arcuate outline. 100

7. A spark plug cleaner comprising an elongated manipulating body member, an arcuate shaped group of flexible scraping prongs projecting directly from one end thereof, and laterally projected scraping edges at the extremities of the prongs. 110

8. A spark plug cleaner comprising an elongated strip of sheet metal of substantially arcuate section having its opposite ends formed as scraping edges, the one pointed inwardly and the other pointed outwardly. 115

9. A spark plug cleaner comprising a body part, and scraper parts having scraping edges, the edges of one of said scraper parts being deflected inwardly to engage the inner wall of a cavity to be cleaned, and those of the other part being deflected outwardly to engage the outer wall of the cavity. 120

10. A spark plug cleaner comprising a body part, a plurality of scraper parts each of approximate arcuate form and comprising flexible prongs, and scraping edges on the ends of said prongs, the edges on cer- 130

tain of said prongs being deflected inwardly to engage and scrape the inner wall of a cavity and the edges of certain others being deflected outwardly to engage and scrape the surfaces of the outer wall of the cavity.

11. A spark plug cleaner comprising an elongated manipulating body of arcuate section, laterally separated flexible prongs in longitudinal extension of each end thereof,

and laterally projecting scraping edges at 10 the extremities of the prongs, those edges at one end of the body being projected inwardly and those edges at the other end of the body being projected outwardly.

In testimony whereof I hereunto affix my 15 signature.

JOHN P. TARBOX.
